CLAIM

The ornamental design for a portion of a chair, as shown and described.

DESCRIPTION

FIG. 1 is an upper perspective view of an exemplary embodiment of a chair;

FIG. 2 is a lower perspective view of the chair shown in FIG. 1;

FIG. 3 is front view of the chair shown in FIG. 1;

FIG. 4 is a rear view of the chair shown in FIG. 1;

FIG. 5 is a left-side view of the chair shown in FIG. 1;

FIG. 6 is a right-side view of the chair shown in FIG. 1;

FIG. 7 is a top view of the chair shown in FIG. 1; and

FIG. 8 is a bottom view of the chair shown in FIG. 1.

The broken lines shown in the figures are for illustrative purposes only and form no part of the claimed design.
